UNITED STATES PATENT OFFICE.

WILLIAM BEDELL CHRISTOPHER, OF RAHWAY, NEW JERSEY.

MARINE PROPELLER.

1,293,035.

Specification of Letters Patent.

Patented Feb. 4, 1919.

Application filed October 19, 1917. Serial No. 197,437.

To all whom it may concern:

Be it known that I, WILLIAM B. CHRISTOPHER, a citizen of the United States, residing at Rahway, in the county of Union and State of New Jersey, have invented new and useful Improvements in Marine Propellers, of which the following is a specification.

This invention comprehends generally improvements in marine propulsion and more particularly has reference to a marine propeller of the endless type.

As the primary aim and object the present invention contemplates the provision of a device of the above mentioned character wherein a plurality of paddles of novel construction are operably connected to endless chains mounted beneath the bottom of a boat for assuring an effective propelling of the boat during the operation of the chains.

It is an equally important object of this invention to provide a marine propeller wherein improved means is employed for carrying the paddles between the chains and for bracing the paddles with respect to the chains so as to increase the longevity and efficiency of the device.

As a further improvement this invention embraces the provision of a marine propeller of the above character wherein the sprocket wheels are of improved construction and are designed to coöperate with the chains in supporting the paddles.

Among the other aims and objects of this invention may be recited a device of the above mentioned character wherein the parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:—

Figure 1 is a longitudinal sectional view of the invention applied to a boat.

Fig. 2 is a top plan thereof, the casing or trunk being shown in section.

Fig. 3 is a transverse section taken on line 3—3 of Fig. 1.

Fig. 4 is a perspective detail of the paddles.

Fig. 5 is a sectional detail of one of the paddles.

Fig. 6 is a perspective detail of one of the sprocket wheels.

Fig. 7 is another perspective detail.

Similar characters of reference are employed in all of the above described views, to indicate corresponding parts.

Referring now, more particularly, to the accompanying drawings, there is provided a boat 1, the bottom of which is provided near the stern with an opening 2 above which is formed an inverted casing, or trunk 3 for the propeller indicated generally by the numeral 4. Guard flanges 5 depend from the bottom of the boat at the sides of the opening and extend longitudinally of the boat serving to protect the propeller and facilitating the operation of the latter, as will become fully apparent.

In the present instance the propeller consists of a pair of shafts 6 positioned transversely of the casing 3 and journaled in opposite sides thereof. Sprocket wheels 7 the bodies of which may be and preferably are similar to automobile wheels are now mounted rigidly in spaced relation on the shafts 6 and each includes a hub 8 from which radiates spokes 9 connected at their outer ends by a felly 10. The felly is formed with a peripheral groove 11 to receive throughout arcuate sprocket plates 12 while flanged rims 13 are disposed on the felly 10 upon opposite sides of the groove as indicated in the drawings and these plates and rims are secured to the felly by transverse fasteners 14. Endless chains 15 operate about the alining sprocket wheels 7 on the shafts 6 and each of the chains is preferably composed of a plurality of opposed links or cheeks 16 and fillers 17 pivoted between the links adjacent the outer ends thereof by pins 18 and by elongated rods 19 which preferably engage one end of every other link and the end of the adjacent filler 17 besides serving to connect the chains on the alining sprocket wheels 7 as indicated, and these rods are held in position by fasteners such as cotter pins 19' which pass through the outer ends thereof. Sectional

paddles 20 are now employed and each comprises a pair of sections 21 and 22 of a rectangular configuration. Channel shaped reinforcing and connecting elements 23 and 24 are now secured to the ends of the sections 21 and 22 by means of fasteners such as bolts 25 and are also formed on their adjacent inner ends with ears 26 which are movably arranged about the respective ends 10 of each of the elongated rods 19 near the inner surfaces of the inner links 16 as indicated.

As intimated, improved means have been employed for bracing the relatively movable sections of each paddle so that they will be held substantially rigid when moving between the sprocket wheels yet will be permitted to move relative to each other when moving above the sprocket wheels. In reducing this feature of the invention to practice headed bolts 27 are mounted so as to project through the countersunk openings 28 positioned adjacent the outer ends of the intermediate portions of the sections 23 and 24 and have their heads abutting the adjacent ends of the sections 21 and 22. Bracing rods 29 have their respective looped ends 30 arranged about the bolts 27 and the respective ends of the elongated rod 19 arranged between the sections of the adjacent paddle as illustrated in the drawings. Fasteners 31 engage the bolts 27 and removably hold the rods to the latter as is apparent.

A main shaft 33 is rotatably mounted in the boat and is adapted to be rotated by a suitable engine 34 while transmission means indicated in its entirety by the numeral 35 is arranged between the engine and the shaft. A gear 36 is carried by the outer end 35 of the shaft 33 and meshes with another gear 37 on the projecting end of the rear shaft 6.

In use, upon starting of the engine 34 the shaft 33 will be rotated the speed thereof being controlled by the transmission mechanism 35 and inasmuch as the shaft 33 is operably connected with the rear shaft 6 the latter will be also rotated. Since the sprocket wheels 7 are carried by the rear shaft the endless chains with the paddles thereon will operate thereabout, and also about the other sprocket wheels on the front shaft 6 to consequently propel the boat as is apparent.

It is believed in view of the foregoing description that a further detailed description of the operation of the invention is entirely unnecessary. Likewise it is thought that the advantages of the invention will be readily apparent.

As many changes could be made in the above described construction and many apparently widely different embodiments of this invention could be made without departing from the scope thereof and it is intended

that all matter contained in the above description or shown in the accompanying drawings shall be interpreted as illustrative and not in a limited sense. It is also to be understood that the language used in the following claims is intended to cover all the generic and specific features of the invention herein described and all statements of the scope of the invention which as a matter of language might be said to fall therebetween.

Having thus fully described this invention, what is claimed as new and desired to be secured by Letters Patent is:

1. A marine propeller including a pair of spaced rotatable shafts, spaced sprocket wheels carried thereby and alining with each other, endless chains operating about the sprocket wheels, a plurality of rods connecting the chains at uniformly spaced intervals, a plurality of paddles, each of the paddles being composed of a pair of sections movably connected to the adjacent rods, and brace rods movably connected to the outer ends of the sections and to the connecting rods.

2. A marine propeller including a pair of rotatably mounted shafts, spaced sprocket wheels carried thereby and arranged in alinement with each other, endless chains operating about the sprocket wheels, rods connecting the chains, a plurality of paddles each of which consists of a pair of sections, elements swingingly connected to each of the rods and movable relative to each other and designed to removably receive and retain the sections of one of the paddles, and bracing rods movably connected to the outer ends of the sections and to the adjacent connecting rods.

3. A marine propeller including a pair of spaced rotatable shafts, spaced sprocket wheels carried thereby and arranged in alinement with each other, endless chains operating about the sprocket wheels and embodying a plurality of spaced links, a filler between the links, and pins connecting certain of the links and filler, connecting rods between the chains and passing through one end of every other opposed pair of links and the adjacent filler, a plurality of sectional paddles each of which consists of a pair of sections, channel shaped reinforcing elements swingably connected to the respective ends of the rods and positioned near the inner sides of the chains and designed to receive the sections of each paddle, fastening means for removably holding the paddle sections within the reinforcing elements, and bracing rods movably connected to the outer ends of the sections and to the connecting rod between the adjacent sections.

4. A marine propeller including a pair of spaced rotatable shafts, spaced sprocket wheels carried thereby and arranged in alinement with each other, endless chains

operating about the sprocket wheels embodying a plurality of spaced links, fillers between the links and pins connecting certain of the links and fillers, connecting rods 5 arranged at uniformly spaced intervals between the chains and passing through one end of every other opposed pair of links and the adjacent filler, a plurality of sectional paddles each of which consists of a pair of 10 sections, channel shaped reinforcing elements having openings in their intermediate portions and near their outer ends, ears formed at the adjacent inner ends of the elements for swinging engagement with the respective ends of the rods and at points near 15 the inner sides of the chains, the side portion of the channel shaped reinforcing elements being provided with opposed alining openings, the sections of each paddle being arranged within the reinforcing elements 20 and formed near their ends with openings for registering with the openings in the sides of the reinforcing elements, bolts projecting outwardly through the openings in the intermediate portions of the channel shaped ele- 25 ments, fastening bolts for engagement with the alining openings in the side portions of the reinforcing elements and with the openings in the sections for removably holding the sections in position, bracing rods having 30 their looped terminals arranged about the ends of the connecting rods and the ends of the bolts which project through the intermediate portions of the receiving elements, and fasteners for retaining the bracing rods 35 against displacement.

In testimony whereof I affix my signature.
WILLIAM BEDELL CHRISTOPHER.
